UNITED STATES PATENT OFFICE.

OSSIAN T. WAITE, OF OSHKOSH, WISCONSIN, ASSIGNOR TO WAITE GRASS CARPET CO.,
OF OSHKOSH, WISCONSIN, A CORPORATION OF WISCONSIN.

GRASS-TWINE MACHINE.

1,019,383.

Specification of Letters Patent.

Patented Mar. 5, 1912.

Application filed April 4, 1911. Serial No. 618,825.

To all whom it may concern:

Be it known that I, OSSIAN T. WAITE, a citizen of the United States, residing at Oshkosh, in the county of Winnebago and State of Wisconsin, have invented certain new and useful Improvements in Grass-Twine Machines, of which the following is a specification.

The mechanism embodied in the present invention is employed more particularly in the selecting and feeding of grasses from the holder into position to be acted upon by the mechanism for forming it into a twine or cord; and the portions of the above mentioned mechanisms which are deemed more particularly to embody the subject-matter of the present invention are the mechanism for packing or feeding the grass downward in the holder and the mechanism for combing out the grasses prior to their interposition into the feed rolls, whereby the entrance of the grasses into the feed roll in a crossed or bunched condition is eliminated.

The objects of the present invention are, to provide a packer which will operate upon the mass of grasses so as to crowd them in the direction most expedient for their insertion into the selector mechanism; and to provide means for automatically pulling out the ends of such grasses as are too short to be engaged by the selecting mechanism.

Another object of the invention is to provide means for subjecting the ends of the grasses to a combing operation prior to their deliverance into the feed rolls, whereby the entrance of the grasses into the feed rolls in proper parallel condition is insured.

A further object of the invention is to provide mechanism whereby a proper feeding of the grasses can be had without assorting the grasses to determine whether they are of proper length to engage with the feeding mechanism.

A still further object is to arrange the combing mechanism so that it will not interfere with the feeding operation, and so that the combing operation will take place at a point close enough to the feeding members that the grasses will not lose the condition of parallelism in which they are placed by the combing operation before their engagement by the feeding members.

The invention further consists in the features of construction and combination of parts hereinafter described and claimed.

In the drawings, Figure 1 is a side view of the mechanism of the present invention and a portion of the grass twine machine to which it is applied; and Fig. 2 is a section on line 2—2 of Fig. 1, looking in the direction of the arrow.

In the art of making grass twine, it has been found necessary to exercise care in the selection of the grasses which are placed in the holder, so as to eliminate the placing of short lengths of grasses, it having been found that the short lengths would not feed properly to the binding mechanism, with the result that a lumpy twine would be produced. In order to form a smooth and even twine, the grasses must be fed to the binding mechanism in a thin, even stream, and to feed in this manner a condition of parallelism must be maintained in the grasses. If the grasses should become crossed or matted, it would result in the placing of more grasses in one portion of the twine than in another, hence making an uneven or lumpy formation in the resultant product, which is undesirable. This selecting of the grasses to obtain those of a proper length requires considerable time and care and is the cause of considerable trouble and confusion in manufacture.

One of the points which makes the present invention of value is the fact that, by using the mechanisms of the present invention, the operator need not exercise care in placing the grasses in the holder, since the mechanism will automatically eject such grasses as are too short to come into engagement with the selecting mechanism, and will keep in straight condition such of the grasses as do not have proper support to keep them in straight position while entering the feed rolls. In the feeding of these grasses, if the grass is of a length so that it is not firmly supported in the holder, the end of the grass will be flexible to a greater or less degree, and hence the end of the grass which is carried by the selecting mechanism will not maintain itself in straight position, but will be liable to become flexed or bent so as to overlap the grass lying to one side or the other of it. Thus, when these grasses enter the feed rolls in this overlapped condition, in place of the grass from one tooth being withdrawn at a time from the selector mechanism, grasses from two or three teeth will be withdrawn, and hence a lumpy formation produced in the resultant twine.

105

110

The mechanisms of the present invention are mounted upon a framework, comprising a table 3 and a support 4. The particular form of table and support here shown is 5 not a part of the present invention, and it may be changed as desired, or the mechanism may be mounted in any other desirable manner. Secured to the support 4 is an arm-like member 5, upon which are mounted 10 vertically extending rods 6 which form a holder 7 for the grasses. The grass within the holder passes out through a mouth or opening 8, best shown in Fig. 2, and in order to crowd the grasses downwardly in the holder, so as to enable them to be brought 15 into said opening, vibrating members 9 and 9^a are provided, which, as shown, are located upon opposite sides of said holder.

The member 9 is in the form of a plate 10, 20 which is provided with a series of beveled teeth 11, having the beveled portion 12 upon the lower edge thereof. This plate is vibrated through the medium of a connection 13, actuated by an eccentric 14 driven from 25 a shaft 15. The member is operated to swing inwardly toward the center of the holder; and the sloping faces 12 will exert a pressure upon the grasses, tending to force or pack them downwardly in the holder, thus forcing 30 them out of the mouth 8. This particular style of packer is shown in my application, Serial No. 550,868, filed March 22, 1910, and is not claimed as a portion of the present invention, but only in combination with 35 the member 9^a, should it be advisable to employ it. The member 9^a, however, is deemed by me to be novel, and is claimed as a portion of the present invention.

The member 9^a is of an elongated plate-like formation, and comprises a body portion 16 terminating in a flat acting-face 17. The body portion is mounted within a support 18, and has connected thereto a link 19 attached to a walking-beam lever 20, actuated by a rod 21, the walking beam being supported by a fixed bar 22. The rod 21 is actuated from the eccentric 14. In the construction shown, the members 9 and 9^a are operated alternately, the member 9 first 45 swinging inwardly and packing the grasses down in the holder, after which the member 9^a acts to crowd the grasses more forcibly into the mouth 8. The member 9 acts upon the entire mass of grass, whereas the member 50 9^a acts only upon those grasses which are adjacent to the bottom of the holder. The member 9^a, being mounted within guideways, moves with a vibrating rectilinear movement. It does not enter into the mass 55 of grasses, but rather engages the outer portion of the mass and presses the entire mass into the mouth 8.

A plate 23, having a beveled edge 24, which constitutes one wall of the mouth 8, is provided with a curved face 25, adjacent to

which operates the edge of a disk 26, provided with a series of notches 27. This is what may be termed the selector disk. This disk, as well as the plate 24, is shown in my former patent heretofore referred to, and is not claimed as a portion of the present invention. The disk 26 revolves, and the teeth 27 pick out a selected number of the blades of grasses, which may be projecting beyond the lower edge of the mouth 8, and carry 75 them downward into engagement with the feed rolls 28, which, in the form shown, are provided with opposed concave and convex surfaces. These feed rolls are also shown in my application heretofore referred to and 80 are not claimed as a part of the present invention.

One of the feed rolls in the form shown is provided with a surface 29, upon which is mounted a series of spikes or teeth 30, which 85 form a comb for disentangling any matting or massing of grasses which may occur prior to the entrance of the grasses into the feed rolls. The selecting disk 26 operates to flex the ends of the grasses so as to carry them 90 out of the holder and down into position to be engaged by the feed rolls, the action of the feed rolls completing the removal of the grasses from the holder. It sometimes happens that the grasses, because of their short 95 length, are not firmly supported in the body of the holder, so that while they are being carried by the selecting disk, owing to the lack of support, their ends may flex or bend so as to overlap and lie upon the grass or 100 grasses in the next adjacent tooth of the selecting disk. If they are allowed to enter the feed rolls in this condition, in place of only the grass in that particular tooth being drawn out and fed forward, the grasses lying 105 within both of the teeth, that is, the overlapping grass and the straight grass, will be fed forward simultaneously, thus feeding a greater mass of grass than is intended, and so producing a bunching in the twine. 110

As will be seen more clearly in Fig. 2, the teeth 30 are lying so that during their revolution they intersect the path of travel described by the ends of the grasses while they are being carried by the selecting disk, so 115 that as the ends of the grasses are carried downward by the selecting disk they are subjected to a combing action by having these spikes or teeth pass through them. If they are in an overlapped and tangled condition, they will be straightened out by these toothed members and will enter the bite of the feed rolls in a straight and parallel condition, so that the feed rolls will grasp the load of each tooth separately and the grasses 120 will be fed through the feed rolls in a continuous, even stream, which will produce an even and smooth cord. It will be noticed that the grasses are subjected to this combing action just prior to their entrance into 125

the feed rolls, so that they will not have time to resume their previously tangled condition after being once subjected to the combing operation; but will enter the feed rolls in the straight and parallel condition in which they have been placed by the action of the teeth 30. By the use of this combing member, grasses which are long enough to engage with the selecting mechanism, but which may not be long enough to have a firm support in the holder, can be maintained in parallel arrangement as so to properly enter into the bite of the feed rolls, thus eliminating the necessity for separating these short lengths of grasses prior to the operation of making the twine.

It will be noted that the member 9^a is acting in a line which is tangential to the disk 26, so that the movement of this member 20 tends to crowd the grasses directly into the teeth of the disk, thus insuring each tooth receiving its full load of grass each time it passes by the lower end of the mouth 8.

Secured to the framework is a shaft 31, 25 power-driven by suitable means, which operates an eccentric 32, provided with a depending rod 33 which passes through a guide member 34; and the eccentric has secured thereto and extending upwardly 30 therefrom a rod 35, which enters into a block 36 from which projects a rod 37 having a bent end 38, shown in dotted lines in Fig. 2, which end, as shown in Fig. 1, lies adjacent to the lower portion of the holder 35 and somewhat removed from the forward end thereof. Both the rod 37 and the rod 35 are adjustable within the block 36, and are held in adjusted position by suitable set-screws 39. This block shows one means for 40 effecting the adjustment of the rod 37, so as to move its hooked end into any desired position within the holder. The function of this hooked end 38 is to pull out from the holder the ends of any grasses which are too 45 short to reach to the selecting disk. Difficulty has been experienced with these extremely short grasses, in that they accumulate and choke the mouth leading from the holder to the selecting disk, and frequently 50 it is necessary to stop the machine in order to remove them. By the utilization of this hooked rod, these grasses are jerked away from the mouth and are flexed or bent so as to have their ends lie below the holder, and 55 the operator can easily grasp them and pull them out from the holder without any cessation in the operation of the machine.

By the utilization of a rod such as the rod 33, which extends within the guide member 34, a four-way motion is imparted to the hooked end 38 by the operation of the eccentric, so that said hooked end moves up, then inward into the mass of grass, then downward, and then out again through said mass, 65 with what may be termed a raking opera-

tion, and pulling the short ends, which are not held by the selector, out from the mass into position where they may be removed from the holder.

I claim:

1. In a grass twine machine, the combination of a holder for grasses, mechanism for feeding the grasses longitudinally of themselves, selecting mechanism for carrying the ends of the grasses out of the hopper into position to be engaged by the feeding mechanism, and means for straightening out the ends of the grasses carried by the selecting mechanism, whereby they separately enter the feeding mechanism, substantially as described. 70

2. In a grass twine machine, the combination of a holder for the grasses, a selecting mechanism for flexing the ends of the grasses to carry said ends out from the mass of grasses within the holder, mechanism for feeding the grasses longitudinally of themselves, and means for subjecting the ends of the grasses to a combing action during the flexing operation, whereby they enter the feeding mechanism in parallel arrangement, substantially as described. 80

3. In a grass twine machine, the combination of a holder for grasses, means for feeding the grasses longitudinally of themselves, selecting mechanism for carrying the ends of the grasses out of the hopper and into position to be engaged by the feeding mechanism, and mechanism operatively connected to the feeding mechanism for straightening out the ends of the grasses carried by the selecting mechanism, causing them to separately enter the feeding mechanism, substantially as described. 95

4. In a grass twine machine, the combination of a holder for grasses, mechanism for feeding the grasses longitudinally of themselves, selecting mechanism for conveying the ends of the grasses from the holder into position to enter the feeding mechanism, and a member carried by the feeding mechanism for straightening out the ends of the grasses carried by the combing mechanism, whereby they separately enter the feeding mechanism, substantially as described. 105

5. In a grass twine machine, the combination of feed rolls for feeding the grasses forward, a portion of the surfaces of at least one of said rolls being provided with teeth adapted to engage the grasses prior to their entrance into the feed rolls, whereby they are subjected to a combing action prior to the feeding operation and enter the feed rolls in parallel arrangement, substantially as described. 110

6. In a grass twine machine, the combination of a holder for grasses, mechanism for feeding the grasses longitudinally of themselves, selecting mechanism for convey- 120

125

130

- ing the ends of the grasses out of said holder and into position to be engaged by the feeding mechanism, and an endless member provided with a toothed surface adapted to engage the ends of the grasses carried by the selecting mechanism and straighten them out, whereby the grasses separately enter the feeding mechanism, substantially as described.
10. 7. In a grass twine machine, the combination of a grass holder, mechanism for feeding the grasses longitudinally of themselves, selecting mechanism for conveying the ends of the grasses out from the holder into position to engage with the feeding mechanism, and means located intermediate the feeding mechanism and the selecting mechanism, said means operating to straighten out the ends of the grasses carried by the selecting mechanism, whereby they separately enter the feeding mechanism, substantially as described.
8. In a grass twine machine, the combination of a holder for grasses having a throated outlet, a rectilinearly moving vibrating member lying out of alignment with said opening for pressing said grasses downward in the holder and into said outlet, and means operatively connected for operating said member, substantially as described.
9. In a grass twine machine, the combination of a holder for the grasses, a rectilinearly moving oscillating member for pressing said grasses downward in the holder, means operatively connected for operating said member, a vibrating cam-faced member opposed to said oscillating member, and mechanism operatively connected for forcing said cam-faced member into and out of the mass of grasses, substantially as described.
10. In a grass twine machine, the combination of a holder for the grasses, a flat-faced plunger-like member for pressing said grasses downward in the holder, means operatively connected for actuating said member with an oscillating rectilinear movement, a vibrating cam-faced member opposed to said oscillating member, and mechanism operatively connected for forcing said cam-faced member into and out of the mass of grasses, substantially as described.
11. In a grass twine machine, the combination of a holder for the grasses having a throated outlet, a rectilinearly-moving oscillating member for pressing said grasses downward in the holder and into said outlet, said member extending obliquely to the grasses within the holder and to said outlet, and means operatively connected for actuating said member, substantially as described.
12. In a grass twine machine, the combination of a holder for grasses having a throated outlet, means for conveying the ends of the grasses out of said outlet, a rectilinearly-moving oscillating member for pressing said grasses downward in the holder and into said outlet, said member operating in a line oblique to said outlet and approximately parallel to the initiatory line of movement of the grasses out of the holder, and means operatively connected for actuating said member, substantially as described.
13. In a grass twine machine, the combination of a holder for the grasses, a rectilinearly-moving oscillating member for pressing said grasses downward in the holder, means operatively connected for actuating said member, a vibrating cam-faced member opposed to said vibrating member, and mechanism operatively connected for forcing said cam-faced member into and out of the mass of grasses, substantially as described.
14. In a grass twine machine, the combination of a holder for the grasses having a throated outlet, a plate-like member terminating in a flat-face lying obliquely to said outlet, and adapted to engage the grasses and press them downward in the holder and into said outlet, a guide for said presser member, and mechanism operatively connected for actuating said member with a rectilinearly vibrating movement, substantially as described.
15. In a grass twine machine, the combination of a holder for the grasses, a plate-like member terminating in a flat-face, adapted to engage the grasses and press them downward in the holder, a guide for said member, mechanism operatively connected for actuating said member with a rectilinearly oscillating movement, a vibrating cam-faced member opposed to said oscillating member, and mechanism operatively connected for forcing said cam-faced member into and out of the mass of grasses, substantially as described.
16. In a grass twine machine, the combination of a holder for grasses, a selecting mechanism for moving the ends of said grasses out of said holder, a vibrating member located between the end of the holder and the selecting mechanism and having an acting end adapted to enter the mass of grasses lying between the holder and the selecting mechanism to pull out those grasses too short to be engaged by the selecting mechanism, and means operatively connected for actuating said member, substantially as described.
17. In a grass twine machine, the combination of a holder for grasses, a selecting mechanism for moving the ends of said grasses out of said holder, a vibrating hooked end member located between the end of the holder and the selecting mechanism and having an acting end adapted to enter

the mass of grasses lying between the holder and the selecting mechanism to pull out those grasses too short to be engaged by the selecting mechanism, and means operatively connected for actuating said member, substantially as described.

18. In a grass twine machine, the combination of a holder for grasses, a selecting mechanism for moving the ends of said grasses out of said holder, a vibrating hooked end member located between the end of the holder and the selecting mechanism

and having an acting end adapted to enter the mass of grasses lying between the holder and the selecting mechanism to pull out those grasses too short to be engaged by the selecting mechanism, means operatively connected for actuating said member, and means for adjusting the position of the hooked end member, substantially as described.
